UNITED STATES PATENT OFFICE.

CARL HENDERSON, OF CHICAGO, ILLINOIS, ASSIGNOR TO MIEHLE PRINTING PRESS AND MANUFACTURING COMPANY, OF CHICAGO, ILLINOIS, A CORPORATION OF ILLINOIS.

GEARING MECHANISM.

Application filed February 1, 1922. Serial No. 533,191.

To all whom it may concern: .

Be it known that I, CARL HENDERSON, a citizen of the United States, residing at Chicago, in the county of Cook and State 5 of Illinois, have invented certain new and useful Improvements in Gearing Mechanism, of which the following is a specification.

This invention relates to printing presses, 10 and more particularly to gearing mechanism for driving various parts of the press, and particularly the vibrator, inking and rider rolls.

As is well known, whenever a printing 15 press is tripped, it is necessary to trip or move the inking rolls out of engagement with the form member or cylinder for preventing an excessive supply of ink, being deposited thereon. It is also desirable to 20 keep the inking, vibrator and rider rolls in motion when tripped away from the form cylinder. This is old practice, but heretofore in so doing the relatively small gears 25 for driving the vibrator, inking and rider rolls have been drawn away from their main 30 associated driving gear an amount not quite sufficient to force said gears out of mesh, but enough to give a relatively great amount of play between the teeth of the intermeshing 35 gears and causing considerable wear of the teeth and also a great amount of noise.

Accordingly, one object of my present invention is to overcome the wear of the gear teeth in question and to overcome the undesirable noise mentioned, and at the same 40 time provide a gearing arrangement which is simple, durable and efficient and adapted to meet all of the requirements for successful commercial use.

This and other objects are accomplished 45 by means of the arrangement disclosed on the accompanying sheet of drawings, in which—

Figure 1 is a fragmentary end elevation 50 of a printing press of the offset type embodying my invention; and,

Figure 2 is a fragmentary vertical sectional view, some of the parts being in elevation.

The various novel features of my invention will be apparent from the following description and drawings and will be particularly pointed out in the appended claims.

Referring to the figures of the drawings, it will be noted that I have disclosed my

invention in connection with a printing press having a form cylinder 10, secured to which is a gear 11 which meshes with and is driven by a gear 12 for driving the form cylinder. Cooperating with the form cylinder 10 for inking same are a plurality of inking rolls 13, vibrator rolls 14 and rider rolls 15, all of which are mounted in a frame 16 which is raised in a manner as shown in the copending application of 60 Joseph R. Blaine, Serial No. 492,882, filed August 17, 1921, for the purpose of tripping the ink rolls 13 out of engagement with the form cylinder 10 if it is desired so to do. The vibrator rolls 14 are provided with 65 gears 17 which are driven by a plurality of gears 18, it being understood that the inking rolls 13 and rider rolls 15 are driven by the vibrator rolls 14 as the result of frictional engagement therewith. The gears 18 are 70 driven by a relatively large gear 19 and the degree of mesh between the teeth of gear 19 and gears 18 is maintained constant for the purpose of preventing wear of the teeth of said gears, and also for preventing noise 75 incident to drawing the gears away from each other such that their pitch circles do not have rolling contact.

As mentioned, heretofore when the inking rolls have been tripped out of engagement with respect to the form cylinder 10, the gears have been drawn away from their driving gear with the accompanying disadvantages mentioned, but I have provided an arrangement whereby, even though the inking rolls are tripped, the degree of mesh between the teeth of gears 18 and 19 will be maintained constant. To this end the gear 19 is moved bodily with the frame 16, the gear 19 being in the form of a ring having 80 an annular flange 20 which loosely rides on a hub member 21 secured to the frame 16 in any suitable manner, such as by bolts 22, said hub having a collar 23 on one side and a ring 24 secured to the other side thereof for 85 preventing the gear 19 from being displaced laterally. The gear 19 may be driven by any 90 gear 25.

It will be understood that through the 95 position of drive gear 25 being so near right angles to the direction of lift, the gear 19 will be pulled out of mesh a negligible amount and little wear and little noise will be occasioned. On the other hand, if gears 18 and 19 were separated, the degree of separation 100

ration, wear and noise would be increased beyond a practical limit. The flange 20 of gear 19 is provided with generous oil grooves 26 to which oil is fed through a pipe 27.

5. It is my intention to cover all modifications of the invention falling within the spirit and scope of the following claims.

I claim:

1. In a printing press, the combination of 10 a form member, inking rolls associated therewith, a movable frame in which said inking rolls are mounted, gears through which said rolls are actuated, and a driving gear for said other gears carried by said frame and

15 movable bodily with said gears, when the frame is moved for tripping the inking rolls, to maintain a constant degree of mesh between said gears.

2. In a printing press, the combination of 20 a form member, inking rolls associated therewith, a frame in which said inking rolls are mounted, gears through which said rolls are actuated, and a driving gear for said other gears carried by said frame and 25 movable bodily with the inking rolls, when the latter are tripped away from said form member, to maintain a constant degree of mesh.

3. In a printing press, the combination of

a form cylinder, means for actuating same, inking rolls associated with said form cylinder, gears through which said rolls are actuated, and a driving gear for said other gears movable bodily therewith, when the inking rolls are tripped away from said form member, to maintain a constant degree of mesh. 30

4. In a printing press, the combination of a form cylinder, means for driving same, inking rolls associated with said cylinder, a movable frame in which said rolls are 40 mounted, gears for driving said rolls, and a driving gear for said other gears carried by said frame and movable bodily with said other gears, when the inking rolls are tripped away from said form cylinder, to 45 maintain a constant degree of mesh.

5. In a printing press, the combination of a form member, inking rolls associated therewith, gears through which said rolls are actuated, and a driving gear for said 50 other gears movable bodily therewith, when the inking rolls are tripped away from said form member, to maintain a constant degree of mesh.

Signed at Chicago, Illinois, this 28th day 55 of December, 1921.

CARL HENDERSON.
